Primary Examiner — Daniel Bui*(74) Attorney, Agent, or Firm* — Ware, Fressola, Maguire & Barber LLP**(57) CLAIM**

The ornamental design for a split, non-metallic electrical insulating bushing, as shown and described.

DESCRIPTION

FIG. 1 is a top perspective view of a split, non-metallic electrical insulating bushing showing my new design;
 FIG. 2 is a top plan view thereof;
 FIG. 3 is a lower side elevation view thereof;
 FIG. 4 is an upper side elevation view thereof;
 FIG. 5 is a bottom plan view thereof;
 FIG. 6 is a left side elevation view thereof; and,
 FIG. 7 is a right side elevation view thereof.
